UNITED STATES PATENT OFFICE.

STEPHEN A. DUVALL, OF PENRITH, WEST VIRGINIA.

RAILWAY-SWITCH.

SPECIFICATION forming part of Letters Patent No. 703,772, dated July 1, 1902.

Application filed April 17, 1901. Serial No. 56,233. (No model.)

To all whom it may concern:

Be it known that I, STEPHEN A. DUVALL, a citizen of the United States of America, residing at Penrith, in the county of Hancock 5 and State of West Virginia, have invented certain new and useful Improvements in Railway-Switches, of which the following is a specification, reference being had therein to the accompanying drawings.

This invention relates to certain new and useful improvements in railway-switches, and has for its object to construct a switch which may be conveniently and effectually operated from a car or locomotive.

My invention, while applicable alike to street or steam railways, is herein shown and will be described as employed in connection with a steam-railway, the switch-tongue and movable rail members being connected by levers to throwing devices located at the sides of the track and adapted to be operated by mechanism carried by the locomotive, the particular construction being hereinafter referred to specifically and then particularly 25 pointed out in the claim.

In describing the invention in detail reference is had to the accompanying drawings, forming a part of this specification, and wherein like numerals of reference will be 30 employed to designate like parts throughout the different views of the drawings, in which—

Figure 1 is a top plan view of my improved switch. Fig. 2 is a transverse vertical sectional view of the same. Fig. 3 is a side elevation 35 of the throwing means carried by the locomotive, showing the latter in dotted lines. Fig. 4 is a top plan view of a part of this mechanism. Fig. 5 is an end view thereof. Fig. 6 is a detail plan view of a part of the rack-bar 40 adapted to be operated by the engineer for engagement with the switch-throwing mechanism located at the side of the track. Fig. 7 is a detail perspective view of a part of the head-block which carries the rack-bar.

I will first describe the track mechanism as illustrated in Figs. 1 and 2, in which 1 indicates the switch-tongue, and 2 the movable rail member. Connected to the underneath face of the switch-tongue and the movable 45 rail member is a switch-bar 3, which extends outwardly to one side of the track and is connected at this outer end to an angle-plate 4,

pivotedly mounted on a block or pedestal 5 at the side of the track. The other arm or leg of this angle-plate is pivotally connected 55 to one end of a lever 6, which has its other end rigidly connected to one end of a lever 7, that extends across the track underneath the rails. This end of the lever 6 and of the lever 7 are pivotally connected by a link 8 to 60 a short lever 9, carried by a barrel or sleeve 10, mounted for rotation on a rod or vertical shaft 11, secured on a pedestal 12 at the side of the track. The barrel or sleeve is held against elevation on the rod or shaft by means 65 of a key 14, passed through the shaft near its upper end above the barrel or sleeve. This barrel or sleeve carries two arms 15 16 near its upper end, set thereon to project in different directions and adapted to be engaged by the mechanism carried by the locomotive, the one of said arms being always in position for engagement with said mechanism. The other end of the lever 7 is pivotally connected to a bell-crank 17, pivotally 70 mounted on a pedestal 18, located at the opposite side of the track to the pedestal 12. The other leg or arm of this bell-crank 17 is connected to one end of a lever 19, which lever at its other end carries a pin 20, which 80 engages in a slot 21, provided therefor in an arm 22, secured to a barrel or sleeve 23, rotatably mounted on a shaft or rod 24, secured on a pedestal 25, located at the side of the track substantially in line with the pedestal 85 18. This sleeve or barrel 23 is held against elevation by a key 26, passed through the rod or shaft 24 above the sleeve or barrel, as afore-described for the barrel or sleeve 10. This sleeve or barrel carries an arm 27 to be engaged by the mechanism carried by the locomotive, as will be hereinafter described.

To permit the engineer to throw the switch from the engine or locomotive, I mount at a suitable point, preferably in front of the 95 boiler, a head-block 28, supported by brackets 29 or other suitable means, this head-block carried on its upper face to apertured lugs 30, which receive the operating rod or shaft 31 and support the same at its outer 100 end, this rod or shaft being extended into the cab of the locomotive and provided on its inner end with an operating-wheel 32. The head-block is provided in its upper face with

a slot 33, opening at each end of the block in an aperture 34. Mounted in the slot or runway 33 is a rack-bar 35, the rack of which bar is uppermost, so as to be engaged by a spur 5 gear or pinion 36, that is secured on the shaft or rod 31 between the two lugs 30. The rotating of the rod or shaft 31 by means of the hand-wheel 32 causes the gear or pinion 36 to actuate the rack and move the same outwardly at one end of the head-block, according to the direction in which the shaft or rod 31 is rotated.

When it is desired to operate the switch, the engineer rotates the shaft or rod 31 so as 15 to force the rack-bar outwardly to the desired side of the locomotive. For illustration we will assume that the train is passing to the left, the switch being in position shown in Fig. 1, and the train desires to pass onto the 20 side track. The engineer operates the rod or shaft 31 so as to force the rack-bar outwardly into position where it will engage with the arm 15, thus moving this arm to the position shown in dotted lines in this view and 25 moving the switch-tongue and movable rail member so as to open the switch, the parts assuming the position in this operation as shown in dotted lines.

It will be observed that the switch may be 30 readily operated by hand when desired and that when the switch is set in the correct position and the rack-bar is lying wholly with-

in the head-block the engine or locomotive will be free to pass the switch without engagement of the rack-bar with the actuating- 35 arms carried by the barrels or sleeves at the side of the track.

Having fully described my invention, what I claim as new, and desire to secure by Letters Patent, is—

In a railway-switch, the combination with the pivoted switch-tongue and the movable rail member, of a switch-bar connected to said tongue and rail member, a bell-crank 4 to which said switch-bar is pivotally connected, a lever 7 extending underneath the rails of the track, a bell-crank 17 located at the opposite side of the track to the bell-crank 4 and to which the lever 7 is pivotally connected, a lever 6 connecting the bell-crank 50 4 with the lever 7, a link connecting said lever 7 with a rotatable sleeve mounted at the side of the track, an arm carried by said sleeve, and means carried by the locomotive for engagement with said arm to actuate the 55 switch-tongue and movable rail member, substantially as described.

In testimony whereof I affix my signature in the presence of two witnesses.

STEPHEN A. DUVALL.
